UNITED STATES PATENT OFFICE.

SAMUEL J. MADDOX, OF MINNEAPOLIS, MINNESOTA.

ROTARY ENGINE.

SPECIFICATION forming part of Letters Patent No. 243,145, dated June 21, 1881.

Application filed October 4, 1880. (No model.)

To all whom it may concern:

Be it known that I, SAMUEL JOHN MADDOX, of Minneapolis, in the county of Hennepin and State of Minnesota, have invented certain Improvements in Rotary Engines, of which the following is a specification.

This invention relates to rotary engines; and it consists in the peculiar form of the valve-gear and valves whereby the steam, after doing duty in the cylinder, is forced back into the boiler, as hereinafter set forth. I obtain these results by the use of the mechanism illustrated in the accompanying drawings, in which—

15 Figure I is a side elevation, with the cover removed. Fig. II is a sectional side elevation on the line $x x$ of Fig. I, one of the pistons being shown in section and the other solid. Fig. III is an outside side elevation. Fig. IV is a 20 detached perspective view of the piston-disk. Fig. V is a detached perspective view of a portion of one side of the center plate, showing the arrangement of the cam-groove; Fig. VI, a fragmentary sectional view of a portion of the 25 piston-disk and valves, showing a variation in their method of construction.

A A' are the covers, bolted together to a center plate, B, leaving two open spaces, in which two piston-disks, C C', are journaled on 30 one shaft, D, one piston being set "quartering" to the other, so that one will be taking steam while the other is exhausting, to keep up the application of power to the shaft. On opposite sides of the piston-disks angular notches 35 $a a'$ are cut, in one end of which valves $b b'$ are pivoted, while the other ends of the valves are free to rise and fall in close contact with the curved abutments $c c'$. Beneath each of these valves $b b'$ the piston-disks are cut away, to 40 form flat tracks $d d'$ for small-wheeled carriages to travel back and forth upon. These carriages are arranged with four wheels or rollers, e, at the bottom, resting upon the tracks $d d'$, and two rollers, e', at the top, in contact with the under 45 side of the valves $b b'$, and all journaled upon one common frame, g, connected by pivoted levers $i i'$ to slides $h h'$, running in straight grooves $k k'$ in the central section of the piston-disks. These slides $h h'$ are each supplied 50 with friction-rollers $h^2 h^3$, adapted to run in a

cam-groove, m, in the stationary center plate, B, (see Fig. V,) by which the friction-carriages are operated, as hereinafter set forth.

On one side of the stationary covers A A', near the bottom, are spring-valves E E' E², 55 connected by a conduit, F, to the boiler, its object to be hereinafter explained.

A little to one side, above the piston-disks, valves G G' are arranged, one for each piston-disk, and provided with stems H H' and cranks 60 H² H³, whose pins run in slots n in rods M M'. These rods run in hangers N N' on the covers A A', and are supplied with friction-rollers r, adapted to be acted upon by double-sided cams P P', which raise the rods M M' and valves G 65 G' upward twice in every revolution of the shaft D. Above the slots n the rods M M' are continued, and end above springs R in casings R', secured to the covers A A', so that the valves G G' will be held back slightly, to prevent their too sudden movement when the steam strikes them. By this arrangement of the slots n n, hangers N N', and spring-cases R' R' the rods M M' are moved in parallel lines. 70

The valves G G' seat into the cavities in the 75 covers A A', from which ports t t' lead into small cylinders T T', in which rolling valves T² T³ are journaled on stems T⁴ T⁵, and connected by cranks T⁶ T⁷ to eccentrics T⁸ T⁹ on the shaft D, by which the valves are oscillated. 80

V is the steam-supply pipe, leading from the center on either side into the cylinders T T'. (See Figs. I and II.) The rolling valves T² T³ are provided with ports t² t³, so that the steam can pass through them, and being arranged to 85 run upon opposite sides of the cylinders T T', the pressure of the steam acting equally on both sides, a perfect "balancing" is produced, so that very little power is required to oscillate them. By providing the two ports t t' the 90 steam will enter through the right-hand ones at the downward strokes of the eccentrics T⁸ T⁹ and through the left-hand ones at the upward strokes, thereby requiring but one complete revolution of the shaft D to supply steam 95 to both valves, b b'.

The operation is as follows: Steam, being admitted through the valves T² T³ and ports t t', presses down the valve G, (the eccentrics T⁸ T⁹ being so set that the abutments c c' will be in 100

the position shown in Fig. I when the steam is admitted,) acts upon the abutment c , and revolves the piston-disks $C C'$ until the pivoted end of the valve b and main body of the piston-disk pass the valve G , when the latter will be forced up into its seat and the steam cut off. From the points m' to m^2 the cam-grooves m are segments of circles parallel with the rims of the piston-disks $C C'$; but from the points m^2 to m' they "dip" toward the shaft D , so that while the rollers $h^2 h^3$ are traveling from m' to m^2 they will remain at the same distance from the shaft, but when the point m^2 is reached they will be drawn inward, and thus, through the levers $i i'$, run the carriages $e e'$ outward along the tracks $d d'$, and raise the valves $b b'$ out toward the inside of the covers $A A'$, and thus force the steam out through the valves $E E' E^2$ and conduit F , back into the boiler, thus utilizing it fully. When the rollers $h^2 h^3$ have passed the center of the dipping portions of the cam-grooves m they will be again returned to their former position at m' , and run the carriages $e e'$ back again, and allow the valves $b b'$ to fall back, ready for the next movement of the valves G . As before stated, the two piston-disks $C C'$ will be set quartering, so that when the first valve, b , of the first piston-disk, C , has passed the first valve, G , and the steam on that side been shut off, the first valve, b , on the second piston-disk, C' , will be just ready to take steam, so that the power is applied to the shaft D continuously. By this arrangement of the carriages $e e'$ the greatest possible amount of friction is avoided; hence little power will be required to operate them, and by re-

turning the steam to the boiler a great saving is obtained and the annoying exhaust-steam avoided.

Fig. VI shows a slight variation in the manner of constructing the piston-disks with a circular instead of a square cross-section, and a square instead of an inclined abutment, c . 40

In using the square abutment it will be necessary to introduce lifting-segments b^2 underneath the valves $b b'$, to prevent the steam entering behind them; but the operation of both forms is substantially the same. 45

By using the circular disk, packing-rings u may be used, as in ordinary engines. 50

What I claim as new is—

1. The combination and arrangement of the piston-disks C , having the valves $b b'$, adapted to be thrown outward at every revolution, and the valves $E E' E^2$, connected to a conduit, F , 55 leading to the boiler, whereby the steam, after doing duty in the engine, is returned to the boiler, substantially as set forth.

2. The combination and arrangement, with the stationary covers $A A'$ and center plate, B , 60 provided with the cam-groove $m m' m^2$, of the revolving piston-disks $C C'$, having grooves $h h'$, and the valves $b b'$, friction-carriages $e e'$, g , levers $i i'$, slides $h h'$, and friction-rollers $h^2 h^3$, substantially as set forth. 65

In testimony whereof I have hereunto set my hand in the presence of two subscribing witnesses.

SAMUEL JOHN MADDOX.
